UNITED STATES PATENT OFFICE.

GIULIO MARCHETTI, OF HALIFAX, ENGLAND.

DESIGN FOR CARPET.

SPECIFICATION forming part of Design No. 23,439, dated July 10, 1894.

Application filed April 17, 1894. Serial No. 507,926. Term of patent 3½ years.

To all whom it may concern:

Be it known that I, GIULIO MARCHETTI, a subject of the Queen of Great Britain, and a resident of Halifax, in the Kingdom of England, have invented a certain new and original Design for Carpets, of which the following is a specification.

The accompanying drawing is a face view of a portion of a carpet and border embodying my invention.

My design consists of the body A and border B.

The body A consists of a series of graceful flower sprays interspersed with sprays of smaller leaf and flower forms.

The border B consists of an inner and an outer edge. The inner edge is characterized by large sprays of flower forms interspersed with sprays of smaller flower and leaf forms.

The outer edge of the border is characterized by a line work background upon which are worked large sprays of leaf forms, separated

by scalloped flower forms. The inner edge of the line work background is wavy and along this edge are sprays of larger flower forms, some of which are partly within and partly without the background.

What I claim, and desire to secure by Letters Patent, is—

1. In a design for a carpet, the body substantially as shown and described.

2. In a design for a carpet, the border substantially as shown and described.

3. The design for a carpet, comprising the body A and the border B, substantially as shown and described.

In testimony whereof I have signed my name to this specification in the presence of two subscribing witnesses.

GIULIO MARCHETTI.
